(57) **CLAIM**

The ornamental design for a craft bobbin winder for use with sewing machine, as shown and described.

DESCRIPTION

FIG. 1 is a perspective view of a craft bobbin winder for use with sewing machine, showing my new design;

FIG. 2 is a front elevational view, thereof, the rear elevational view being identical, thereto;

FIG. 3 is side elevational view, the opposite side elevational view being identical, thereto;

FIG. 4 is a top plan view, thereof;

FIG. 5 is a bottom plan view, thereof;

FIG. 6 is a perspective view, thereof, taken from a low angle; and,

FIG. 7 is a perspective view, showing the article in use with a sewing machine.

The broken line representation of the craft bobbin and retaining plug shown in FIGS. 6 and 7, and the broken line representation of the thread and the sewing machine in FIG. 7, are included solely for illustrative purposes, forming no part of the claimed design.
